UNITED STATES PATENT OFFICE.

THOMAS W. KIRKMAN, OF NEW YORK, N. Y., ASSIGNOR TO STANDARD GRAMOPHONE APPLIANCE COMPANY, OF NEW YORK, N. Y., A CORPORATION OF NEW YORK.

DESIGN FOR A BRUSH FOR TALKING-MACHINE RECORDS.

45,883.

Specification for Design.

Patented June 2, 1914.

Application filed March 25, 1914. Serial No. 827,238. Term of patent 14 years.

To all whom it may concern:

Be it known that I, THOMAS W. KIRKMAN, a citizen of the United States, residing at New York city, in the county and State of New York, have invented a new, original, and ornamental Design for Brushes for Talking-Machine Records, of which the following is a specification, reference being had to the accompanying drawings, forming part thereof, wherein—

Figure 1 is a side elevation, Fig. 2 a top

plan view, and Fig. 3 a bottom view of a brush for talking machine records showing my design.

I claim:

The ornamental design for a brush for talking-machine records, as shown.

THOMAS W. KIRKMAN.
